CANISTER FOR GREASE

Elwood A. Neese, West Bend, Wis., assignor to West Bend
Aluminum Co., West Bend, Wis., a corporation of Wis-
consin

Application February 27, 1956, Serial No. 40,369

Term of patent 14 years

(Cl. D44—6)

The figure is a view in side elevation of a canister for grease embodying my new design.

The dominant features of my design reside in the portions shown in full lines.

I claim:

The ornamental design for a canister for grease, substantially as shown and described.
